UNITED STATES PATENT OFFICE.

ERNST F. TROIKE, OF SANDUSKY, OHIO.

TIltTABLE ROUNDABOUT.

Application filed March 1, 1924. Serial No. 696,353.

To all whom it may concern:

Be it known that I, ERNST F. TROIKE, a citizen of the United States, residing at Sandusky, in the county of Erie and State 5 of Ohio, have invented certain new and useful Improvements in Tilttable Roundabouts, of which the following is a specification.

This invention relates to a tilttable roundabout, and particularly to a construction 10 in which a rotating platform or support is diverted from and restored to its path of travel in a horizontal plane during such rotation.

In prior constructions of this character 15 independent driving mechanism has been used for effecting the rotation of the platform and the gyratory movement thereof, and such latter movement effected through a tilting shaft connection. In eliminating 20 the objections to the present constructions it is found desirable to directly drive the platform from a rotatable head by a single motor element and to secure the tilting action through a shaft adjustably mounted 25 upon said head to effect the oscillation thereof about the central axis of the head.

The invention has for an object to provide a novel and improved construction comprising a driven head having a support 30 mounted thereon for universal movement and a shaft connected to the universal joint and to an actuating eccentric in order to provide a continued tilting movement of said shaft during the rotation of the head.

Another object of the invention is to provide an improved construction wherein the driven rotatable head is provided with a universal connection for supporting a platform and a dependent tilting shaft having 40 its lower end mounted in a slide member carried by the head and adapted to be actuated by a link connection eccentrically mounted upon a rotatable member.

A further object of the invention is to 45 provide improved means for mounting the tilttable roundabout so that the rotation and tilting movement thereof may be definitely controlled, or reversed as found desirable or convenient.

Other and further objects and advantages 50 of the invention will be hereinafter set forth and the novel features thereof defined by the appended claims.

In the drawings:

Figure 1 is a vertical section of the invention applied;

Figure 2 is a reduced top plan of Figure 1 with the roof supports in section;

Figure 3 is a detail upon the line 3—3 of Figure 1;

Figure 4 is a central vertical section through the head and platform connections;

Figure 5 is a section on the line 5—5 of Figure 4, and

Figure 6 is a similar view on the line 6—6 of Figure 4.

The invention has been herein disclosed as applied to a rotating and tilting platform for an amusement or recreation apparatus, but is capable of other applications in use and for the support of other carrier members than those specifically shown.

In the form of the invention disclosed, the platform 10 is carried by supporting 75 beams 11 mounted upon a rotatable head 12, as hereinafter described. This head is supported upon a base of any suitable character, for instance comprising the standards 13 provided with a top plate 14 upon

which a master gear 15 is mounted for rotating the head 12. This gear may be provided with a ball bearing comprising a plate 16 provided with apertures in which the bearing balls 18 are disposed and bear 80 upon the plate 14 and the gear 15. This gear comprises a base plate having at its peripheral face the teeth 19 which mesh with a driving pinion 20 carried by the shaft 21 from the power connection to be 90

hereinafter described. The head is secured to this base by means of a flange 22 and attaching devices such as bolts 23, while the upper portion of the head is formed with a flange 24 to which the pivoting plate 25 of the universal joint is secured by bolts 26. This plate is provided with opposite lugs 27 adapted to receive the pivots 28 from a universal joint which also carries oppositely disposed pivots 29 upon which the 95 yoke 30 carrying the supporting beams 11 is mounted. This mounting may be effected in any preferred manner, for instance by means of a clamping plate 31 secured against rotation upon the shank 32 of the 100 yoke 30. Cooperating with the plate 31 is the base plate 33 of the cap 34 and retaining bolts 35 extend between the plates 31 and 33 to securely support the beams or arms 11 in position. The upper portion of 105

this cap 34 is provided with a flange 36 from which the braces or stays 37 extend 110

and are secured at their outer ends 38 to the platform 10, as shown in Figure 1.

The parts so far described provide for a rotary movement of the platform driven 5 through the head, but in order to provide a tilting or gyrating motion during the oscillation a tilting shaft 40 is connected to the upper member of the universal joint by means of a casing 41 secured to the shank 42 of the joint and provided with a bushing 43 in contact with which the upper end 43 of the shaft bears. The lower end of the shaft 40 carries a yoke 44 which is pivotally mounted upon pintles 45 extending from 10 opposite sides of a slide block 46. This block may be of any preferred construction but is herein shown as comprising opposite members provided with a bushing 47 and secured together by the clamping bolts 48 15 so as to have a freely sliding fit upon the slide bar 49 which is secured at its opposite ends to the lugs 50 projecting inward from the side walls of the head 12. This bar may be attached in any desired manner, for instance by bolts as shown at 51.

For the purpose of imparting a reciprocatory movement to this block and consequent tilting of the shaft, a pinion 52 is securely fixed to the top plate 14 carried by the 30 standards by means of an angular shank and clamping nut as indicated at 53. This pinion is fixed relative to the rotatable parts which travel upon a roller bearing 54 surrounding the shaft of the pinion.

35 The master gear or base plate has pivotally supported thereon an eccentric gear 55 mounted upon a post 56 and meshing with the pinion 52 so that in the rotative movement of the master gear this eccentric gear has a planetary movement about the periphery of the pinion. The gear 55 is also provided with a pivot 57 from which a link 58 extends and a depending pivot 59 carried by the sliding block. These several pivots are provided with bushings of the usual character.

For the purpose of preventing any strain or side play during the tilting movement of the platform the standards 13 may be provided 50 with idler wheels 60 which travel upon the flange 22 of the head and are carried by the stub shafts 61 secured to the standard by arms 62.

55 In the assembled relation of the parts shown, the platform 10 is provided with a series of seats 63 to accommodate passengers and these are surrounded by a suitable protecting rail 64 provided with an entrance gate 65 as indicated by dotted lines in Figure 2. The platform is also formed at its periphery with a dependent skirt 66 cooperating with a similar member 67 formed upon the fixed floor 68 of the enclosing structure. This floor may also be provided 60 with a protecting rail 69 having an entrance

opening 70 at one side and an exit 71 at the opposite side. The provision of the cooperating skirt members avoids an open space during the rotation of the platform in its gyrating movement and any danger to passengers incident thereto. 70

As showing a desirable form of driving mechanism the shaft 21 for the pinion 20 may be provided with a gear 72 adapted to be driven by an electric motor 73 from which the circuit connections 74 extend to a proper control apparatus such as the parallel switch members 75 by which the motor may be reversed to change the direction of rotation of the platform. It is also desirable under some conditions to provide a controlling rheostat or resistance as at 76 by which the speed of rotation of the motor may be controlled, this member as well as the switches being in circuit with a power line at 77. It is also found convenient to provide a braking mechanism for stopping the rotation of the platform at the desired point so that the entrance gates will be properly aligned and for this purpose the 80 shaft 21 may be provided with a brake drum 78 embraced by a strap or band 79 connected at one end to an actuating lever 80 from which an operating rod 81 extends to the 85 control station. 90

The entire structure may be suitably enclosed, for instance, by means of a roof 82 suitably supported by uprights 83 extending from the fixed flooring 68 surrounding the 95 rotatable platform 10. 100

In the operation of the invention it will be seen that when the parts are in the position shown in Figure 4 the tilting shaft is substantially in alignment with the axis of the rotatable head and the platform consequently in a horizontal position. The movement of this head causes the eccentric gear to travel upon the pinion and through the link connection therefrom the slide member is reciprocated, carrying the base of the tilting shaft so as to effect a gradual lateral deflection thereof, as indicated by dotted lines in Figure 4, thus producing a continued gyratory or tilting movement of the platform during its rotation and finally restoring the platform to a horizontal position at the termination of the complete travel of the gear about the fixed pinion. 110

The provision at the joint for the platform mounting upon the rotatable head provides a direct driving movement thereof and removes all rotative strain from the tilting shaft which is merely used to effect the oscillatory movement toward and from a horizontal plane. The structure therefore provides a substantial driving connection for the platform in which the parts are positively operated and the tilting movement definitely effected through the slide connection which materially eliminates the 120 125 130

wear and strain incident upon working parts in which the center of weight is changed during their travel.

The driving connections shown provide for the adequate control as to speed and direction of the movement of the platform and by a proper ratio of the gears the extent and period of the tilting movement may be changed as well as the speed of the platform.

While the specific details of construction have been shown and described, still the invention is not confined thereto as changes and alterations may be made without departing from the spirit thereof as defined by the following claims.

Having thus described my invention, what I claim as new and desire to secure by Letters Patent is:—

- 20 1. In a tiltable roundabout, a rotatable head, a universal joint mounted thereon for bodily rotation, a platform support carried by said joint and rotatable about the rotative axis of the head, a shaft depending from said support, and a connection from the head to effect movement of one end of said shaft alternately in opposite directions during continued rotation of the universal joint.
- 25 2. In a tiltable roundabout, a rotatable head, a support mounted thereon for universal movement, a shaft depending from the support, a gear carried by said head eccentric to its axis of rotation, and a link connection therefrom to the lower end of said shaft.

30 3. In a tiltable roundabout, a driven head provided with a support mounted for universal movement thereon, a shaft depending from the support, an eccentric gear carried by said head out of alignment with said shaft, a link connection from said head to the lower end of said shaft, a slide bar mounted in the head, and a box slidable thereon and having pivotal connections to said shaft and to said link.

40 4. In a tiltable roundabout, standards provided with a top plate, a head provided with a master gear and rotatably mounted upon said plate, a pivoting plate carried by the upper portion of said head, a universal joint mounted upon said pivoting plate and having a connection between said joint and gear disposed to travel in a planetary path relative to the rotative axis of the gear, and supporting members rigidly carried by said joint.

45 5. In a tiltable roundabout, standards provided with a top plate, a head provided with a master gear and rotatably mounted upon said plate, a pivoting plate carried by the upper portion of said head, a universal joint mounted upon said pivoting plate, supporting members carried by said joint, a shaft depending from said support-

ing members, a pinion centrally secured to said top plate, an eccentric gear carried by the master gear for planetary travel around said pinion, and a link extending from the eccentric gear to control the lower end of said shaft.

6. In a tiltable roundabout, standards provided with a top plate, a head provided with a master gear and rotatably mounted upon said plate, a pivoting plate carried by the upper portion of said head, a universal joint mounted upon said pivoting plate, supporting members carried by said joint, a shaft depending from said supporting members, a pinion centrally secured to said top plate, an eccentric gear carried by the master gear for planetary travel around said pinion, a link extending from the eccentric gear to control the lower end of said shaft, a cross bar extending diametrically of the head, a boxing slidable mounted thereon, a pivotal connection between said shaft and boxing, and a pivot upon said boxing to receive the link connection with said eccentric gear.

7. In a tiltable roundabout, standards provided with a top plate, a master gear disposed thereon, a head secured to said master gear, a rotatable universal joint having its axes disposed at the upper portion of said head and a depending connection geared from the rotative axis of the master gear to traverse a path planetary thereto, and a supporting structure carried by the upper portion of said joint.

8. In a tiltable roundabout, standards provided with a top plate, a master gear disposed thereon, an intermediate bearing plate carrying balls, a head having a flange secured to said master gear, a universal joint disposed at the upper portion of said head, a supporting structure carried by the upper portion of said joint, and an idler roll carried by the standards and adapted to travel upon the flange of said head.

9. In a tilting roundabout, a rotatable head, a universal joint provided at the upper portion thereof and having a casing socket, a tilting shaft disposed in said socket, a yoke carried by the lower portion of said shaft, a cross bar secured to said head, a slide box mounted upon the cross bar and pivotally connected to said yoke, a pivot depending from said box, a link mounted upon said pivot, a rotatable gear carried by the master gear and having an eccentric connection with said link, and a fixed pinion about which said rotatable gear travels in a planetary path.

10. In a tiltable roundabout, a rotatable platform provided with seats, a driving head carrying a universal joint connection rotatable therewith and supporting said platform, a tilting member connected to a member of said joint and adapted to travel

around the axis of the head, means for shifting said member to effect a rocking movement of the platform, a driving shaft for said head, and a motor therefor adapted to control its speed and opposite directions of travel.

11. In a tiltable roundabout, a rotatable platform provided with seats, a driving head having a universal joint connection rotatable therewith and supporting said platform, a tilting member connected to a member of said joint and adapted to travel around the axis of the head, means for shifting said member to effect a rocking movement of the platform, a driving shaft for said head, a motor therefor adapted to control its speed and opposite directions of travel, and brake means for controlling the movement of said head.

12. In a tiltable roundabout, a rotatable platform provided with seats, a driving head having a universal joint connection with said platform, a tilting member connected to a member of said joint and adapted to travel around the axis, a driving shaft for said head, a motor therefor adapted to control its speed and opposite directions of travel, brake means for controlling the movement of said head, a depending skirt carried by the periphery of said platform, and a cooperating skirt upon the fixed floor surrounding said platform.

13. In a tiltable roundabout, a base carrying a master gear, a head secured thereto, a pivot plate mounted upon said head, a universal joint mounted in said plate, a clamping plate having a yoke mounted upon said universal joint, a casing provided upon said yoke and projecting upwardly therefrom, a cap cooperating with said clamping plate to support radiating arms, and braces extending from said cap to a platform carried by said arms.

14. In a tiltable roundabout, a base carrying a master gear, a head secured thereto, a pivot plate mounted upon said head, a universal joint mounted in said plate, a clamping plate having a yoke mounted upon said universal joint, a casing provided upon said yoke and projecting upwardly therefrom, a cap cooperating with said clamping plate to support radiating arms, a shaft mounted in said casing and depending therefrom, and means for imparting an eccentric movement to the lower end of said shaft.

15. In a tiltable roundabout, a head provided with driving means, a universal joint at the upper portion of said head rotatable therewith, a casing projecting upward from the upper member of said joint, a support carried by said joint, a shaft rotatably mounted in said casing and carrying at its lower end a yoke member, a slide bar mounted upon lugs at opposite sides of the head, a block mounted upon said bar and having pivots disposed in said yoke, and means for reciprocating said block upon said bar to opposite sides of the axis of the head.

16. In a tiltable roundabout, a head provided with driving means, a universal joint at the upper portion of said head, a casing projecting upward from the upper member of said joint, a support carried by said joint, a shaft rotatably mounted in said casing and carrying at its lower end a yoke member, a slide bar mounted upon lugs at opposite sides of the head, a block mounted upon said bar and having pivots disposed in said yoke, means for reciprocating said block upon said bar, a fixed pinion extending through the base of said head, a rotatable gear carried by said base for planetary travel around the pinion, and a link connection eccentrically from said gear to reciprocate said block.

In testimony whereof I affix my signature.

ERNST F. TROIKE.
